INVENTOR:

H. T. Stanard.

United States Patent Office.

H. T. STANARD, OF WAYNE, MICHIGAN.

Letters Patent No. 67,144, dated July 23, 1867.

IMPROVEMENT IN MACHINES FOR APPLYING AND MEASURING FORCES.

The Schedule referred to in these Letters Patent and making part of the same.

TO ALL WHOM IT MAY CONCERN:

Be it known that I, H. T. STANARD, of Wayne, in the county of Wayne, and State of Michigan, have invented a new and useful Machine for Applying and Measuring Forces; and I do hereby declare that the following is a full, clear, and exact description of the construction and operation of the same, reference being had to the annexed drawings, making a part of this specification, in which—

Figure 1 is a plan.

Figure 2 is a longitudinal section.

Figure 3 is a transverse section through the measuring device.

Figure 4 is a transverse section through the frame.

Figure 5 is an isometrical view of the double lever and loops detached and enlarged.

The object of this invention is to obtain a strong and cheap machine, for applying force to tear asunder an iron rod, and at the same time to measure the force in pounds, and also to show how much the rod to be tried extends under a certain amount of force. The machine may be constructed of different sizes and capacity, varying from a few pounds up to many thousands; its power almost beyond limit. The machine may be used to determine the tensile, transverse, or torsional strength, and may be used in a horizontal or perpendicular position; it can also be made portable, and used to move heavy bodies.

Description.

A is a firm foundation of timber, to which the head-blocks B B' are firmly secured. F F F, figs. 1, 2, and 4, is a frame of iron or other suitable material, with holes $\circ\circ\circ$ constructed in three parts so that the fulcrum-pin α may have triple bearings, thereby securing greater strength; said frame is secured to head-block B by the pin I. In this frame the double lever C C, figs. 1, 2, 4, and 5, operates on the movable fulcrum-pin α . $\circ\circ$, fig. 5, are recesses for bearings on the pins. G, fig. 1, is a notched rod pivoted to the frame with the bolt m , and engages the double lever on pin p . The hand-lever H is pivoted to the frame by the bolt m' , and carries the notched rod D and engages with the double lever on pin P. The loops ff , figs. 2 and 5, work easily in the double-lever C C, and connected by the double draw-rod T. S is a scale of equal parts. E, figs. 1, 2, and 3, is a plank or frame, pivoted to the foundation A, with a pin, X. M is a block, fast to the plank E, to which the hook L is fastened. The steelyard arm N has one of its fulcrum bearings at d , and secured to the head-block B' by the pin 2; the other fulcrum bearing is at b , in connection with hook L. The steelyard arm R is connected to arm N by the bar S S; it has a bearing at 1, and fixed to the plank at l . h is an index-wheel, with bearing 9, on which the pointer 3 is firmly fixed, with its point turned up so as to come against the pointer 4, which is loose on the arbor. To the wheel there are fastened two fine chains or cords 5 and 6; the cord 5 is attached to the spring 7, and the cord 6 passes around the wheel and is fastened to the arm R. $o\circ$ are a circular scale.

Operation.

The rod to be tried is to be fastened to the hook L and the rod T, fig. 1. The lever H is moved in the direction indicated by the arrow until the rod D engages P in another notch, then apply some force to the lever H in the opposite direction, until the double lever C is brought in position to engage another notch on rod G; now the pivot-pin n must be removed, the double lever resting for its fulcrum on pin α ; repeat the operation of the hand lever H and rods G and D, until the double lever C is brought in such a position as to permit the pivot-pin to be inserted at r ; then disengage both rods G and D, and move the double lever C in position to insert the fulcrum-pin at k ; this is easily done, for the lever C turns on the pivot n . The operation with lever H is to be repeated again; during this operation the force acts upon the steelyard arm N, and is transmitted to arm R by the bar S S, and turns the index-wheel, and the force in pounds is indicated by the pointer 4 on the circular scale $o\circ$. When the rod breaks the index-wheel turns back, but the pointer 4 remains on the proper number; during the operation the extension of the rod under trial can be noted on scale S.

I do not claim separately the working of the lever in a frame on movable fulcrum; neither do I claim the compound lever. I do not claim any new principle in the steelyard arm, or index, or the spring, separately.

What I claim as my invention, and desire to secure by Letters Patent, is—

1. I claim the frame F F F in triple form, as described.
2. I claim the combination of the double lever C C, with the frame F F F, as specified, to obtain a triple bearing for the fulcrum-pin, thereby securing greater strength.
3. I claim, in combination, the arms N and R, index-wheel h , pointers 3 and 4, scale $o\circ$, chain or cord 5 and 6, spring 7, all combined and operating as specified.

H. T. STANARD.
